(57) **CLAIM**

The ornamental design for a barricade frame, as shown and described.

DESCRIPTION

FIG. 1 is a front elevation view of a barricade frame showing my new design;

FIG. 2 is a rear elevation view thereof;

FIG. 3 is a side elevation view as seen from the right side of FIG. 1, the left side being a mirror image;

FIG. 4 is a top plan view thereof;

FIG. 5 is a bottom plan view thereof;

FIG. 6 is an enlarged partial section taken along the plane of the line 6—6 of FIG. 1;

FIG. 7 is an enlarged partial section taken along the plane of the line 7—7 of FIG. 1;

FIG. 8 is an enlarged partial section taken along the plane of the line 8—8 of FIG. 1;

FIG. 9 is an enlarged partial section taken along the plane of the line 9—9 of FIG. 1; and,

FIG. 10 is an enlarged partial section taken along the plane of the line 10—10 of FIG. 1.
